UNITED STATES PATENT OFFICE.

JULIUS FUCHS, OF VIENNA, AUSTRIA-HUNGARY.

CORSET.

SPECIFICATION forming part of Letters Patent No. 367,140, dated July 26, 1887.

Application filed November 12, 1886. Serial No. 218,741. (No model.) Patented in Belgium August 21, 1886, No. 74,307; in France August 21, 1886, No. 178,106, and in Italy November 20, 1886, No. 20,708/74.

To all whom it may concern:

Be it known that I, JULIUS FUCHS, a subject of the Emperor of Austria-Hungary, residing at Vienna, in the Province of Lower Austria, in the Empire of Austria-Hungary, have invented certain new and useful Improvements 5 in Corsets, (for which Letters Patent have been granted in France, No. 178,106, dated August 21, 1886; Belgium, No. 74,307, dated August 21, 1886, and Italy, No. 20,708/74, dated November 20, 1886;) and I do hereby declare the following to be a full, clear, and exact description of the invention, such as will enable others skilled in the art to which it appertains to make 10 and use the same, reference being had to the accompanying drawings, and to letters or figures of reference marked thereon, which form a part of this specification.

Referring to the drawings, Figure 1 is a perspective rear view of part of a corset showing the arrangement of the lacing-strings or laces and the mode of lacing the corset. Fig. 2 is a like front view of so much of a corset as is necessary to show the front fastenings. Fig. 3 is a face view of a portion of the front stays, showing my improved clasp or clamp on an enlarged scale and in a closed position. Fig. 4 is a transverse section of the stays, showing the clasp by an edge view; and Fig. 5 is a view 25 similar to Fig. 4, showing the stays in their pockets.

The primary object of my invention is to so construct a corset that the same, in cases where it may be too tightly laced, may be loosened to 30 any desired extent without necessitating material exposure of the upper part of the body of the wearer, substantially as hereinafter fully described.

A further object of the invention is to provide means whereby the front stays may be unhooked without necessitating the opening of the dress for that purpose, substantially as hereinafter fully described.

A still further object of the invention is to 45 provide means whereby a corset, if too tightly laced, may be loosened to any desired extent, and, when loosened sufficiently, secured in place to prevent further loosening of the corset, without necessitating the opening of the 50 dress, substantially as hereinafter fully described.

To these ends the invention consists in a novel arrangement of the corset-laces, in the combination therewith of means for adjustably securing the laces, and in the mode of lacing the 55 corset, substantially as hereinafter described, and as set forth in the claims.

The invention further consists in the means for securing the front stays, so that the two halves of the corset may be readily released 60 without necessitating access to the corset, substantially as hereinafter fully described, and as set forth in the claims.

My invention is applicable to any existing style or form of corset made in two halves, laced 65 together in the back and hooked together in front, a portion of my said invention being applicable to that style of corset in which the lacing is the only fastening.

I will first describe the arrangement of the 70 laces, the means of adjusting the same, and the mode of lacing the corset, referring more particularly to Fig. 1 of the drawings.

The corset C shown is composed of two halves, c and c', provided along the back edges 75 with eyelets e e', as usual. Although I may employ a single lace for lacing the corset, I prefer to use two laces, L and L', one for the upper and the other for the lower half of the corset. One end of the lace L is secured to the 80 upper eyelet, e, of the section c of the corset, and one end of the other lace, L', is secured to the lower eyelet, e', of the section c' of said corset.

The laces, instead of being passed zigzag 85 fashion through the eyelets from one section to the other, are passed through said eyelets in the following manner: Taking as an illustration the lace L, the end is passed from the upper eyelet e of section c of the corset directly across to the upper eyelet e' of section c', thence down section c' to the next eyelet thereof, thence across through the second eyelet e of section c, thence down along said section through the third eyelet e, again across 95 through the third eyelet e' of section c', and so on, both laces being laced in the same manner, their ends passing through the center eyelets of the series, as plainly shown in Fig. 1.

It is obvious that in adapting this mode of 100 lacing the path of the laces is less obstructed, and consequently there is less friction, the

laces running freely through the eyelets, so that on releasing either one of the laces the upper or the lower half of the corset may be readily loosened, or said corset may be loosened 5 along the entire length by releasing both the laces. The ends of the laces L and L' may be brought to the front of the corset and there tied, or they may be tied at back, so that should it become desirable to loosen the corset this may be done by simply untying one or both laces.

By simply tying the laces the degree of tightness of the corset can, however, not be regulated very easily, and the untying and 15 retying require more or less lengthy manipulations of the laces. To avoid this I provide means whereby the lace ends may be readily secured and the degree of tightness of the corset adjusted. To this end I attach to the free 20 ends of the strings or laces L and L' a tape or ribbon, l and l', respectively, to which are secured a number of eyelets, e² e³, and at a suitable point on the front stays, S and S', I secure hooks h and h', respectively, Fig. 2, to which 25 the tapes are hooked. When laces proper are employed, the eyelets may be secured directly thereto; but to cause the same to run more freely through the corset-eyelets e and e', I prefer to use lacing-cords, as shown, in which 30 case the eyeleted ribbons or tapes are necessary.

It will readily be seen that when it is desired to loosen either the upper or the lower part of the corset, or to loosen the same the 35 full length, it will only be necessary to unhook the tapes from their hooks, and a slight bend of the body toward the right or left will cause the cords or laces to slip in the eyelets e and e', and when the corset is sufficiently 40 loose the cord ends may again be secured by hooking the tapes to their respective hooks, and this may be effected without opening the body of the dress to any extent.

To provide means for unlocking or unhooking 45 the two halves or sections e and e' of the corset C without opening or removing the body of the dress, I employ a button-hole-locking device B^x, made in two sections, B and B', applied to one of the stays, as the stay S', the 50 stay S being provided with the buttons or studs A, as usual.

The section B of the locking device is rigidly secured to the stay S'. It has the form of a U, from the right-hand leg b⁴ of which 55 projects one-half of the button-hole b, the locking-edge b⁶ of which is perfectly straight and terminates at the left in a semi-cylindrical recess, which constitutes one half of the eye of the button-hole. The section B' of the button-hole-locking device consists of a lever-arm pivoted at its lower end near the leg b⁴ of section B, and a locking-latch, b', having a straight locking-edge, b⁸, terminating on the left in a semi-cylindrical recess, which forms 60 the other half of the eye of the button-hole,

and on the right in a curved lip or nose, b⁷, that embraces the shank of the stud or button A when closed. At its free end the lever-arm of section B' has a stud or button, B², that projects sufficiently from the front face thereof to 7c serve as a hand or finger hold, whereby the section B' is manipulated to unlock the stays. In Fig. 3 I have shown the locking device in its closed position, in which it is held by a spring, s, secured at one end to the upper end 75 of the lever-arm of section B', the free end of the spring abutting against the left leg b⁶ of the U-shank of section B, said free end of the spring being preferably slotted, so as to straddle the leg b⁶, and to be held thereby against 80 displacement.

The manipulating-button B² projects through a slit, p', formed in the pocket P' of the stay S', as shown in Fig. 5. By means of the construction described the unbuttoning of the 85 front stays may be readily effected without opening any portion of the body of the dress by simply moving the section B' by means of the button B² toward the left, and the corset may thus be wholly unbuttoned, or only at a 90 certain point or points, as may be desired.

It is obvious that other forms of pivoted locking devices may be used to effect the same purpose, and such devices need not necessarily be made in two sections, as any well-known form of hook may, for instance, be employed; but I prefer to employ the locking device described, for the reason that it affords the same security as the ordinary button-hole clasp or lock, there being but little or no danger of an accidental unlocking of the corset.

Having now particularly described my invention, what I claim, and desire to secure by Letters Patent, is—

1. In a corset, the combination, with two 105 lacing-strings having one end secured to opposite sides and opposite ends of the meeting edges of the corset and running through the eyelets to the longitudinal center thereof, of fastening devices, substantially as set forth, 110 secured to the front stays of the corset, to which the free ends of the laces or strings are made fast, substantially as described, for the purpose specified.

2. A corset composed of two parts adapted 115 to be laced together in the back and hooked together in front, the combination, with the lacing-string provided with an eyeleted extension, of the front stay provided with a retaining device to which said eyeleted extension is secured, substantially as and for the purpose specified.

3. In a corset, the combination, with two 125 lacing-strings having one of their terminals secured to opposite sides and ends of the meeting edges of the corset and passing through the eyelets along said meeting edges to the longitudinal center, the free ends of the strings being provided with a plurality of eyelets, of retaining devices secured to the front stays of 130

the corset for adjustably securing the strings, substantially as described, for the purpose specified.

4. In a corset, the combination, with the 5 stays, of buttons or studs connected with one of said stays, and a series of locking devices, B^x, carried by the other stay, constructed and adapted to engage the buttons or studs, as described, for the purpose specified.

In testimony whereof I affix my signature in 10 presence of two witnesses.

JULIUS FUCHS.
